UNITED STATES PATENT OFFICE.

JOHN N. MCLEAN, OF NEW YORK, N. Y.

AIR-PUMP.

SPECIFICATION forming part of Letters Patent No. 642,354, dated January 30, 1900.

Application filed January 13, 1896. Serial No. 575,381. (No model.)

To all whom it may concern:

Be it known that I, JOHN N. MCLEAN, a citizen of the United States, and a resident of New York, in the county and State of New York, 5 have invented certain new and useful Improvements in Air-Pumps, of which the following is a specification.

My invention relates to air-pumps for forcing or compressing air or other elastic fluids 10 and of the class suitable for hand operation.

The objects of my improvements are, first, a construction that is neat, light, contained in small space, and easily portable; second, to provide an actuating mechanism in which is a 15 lever pivoted to a fixed fulcrum in a suitable position in relation to the cylinder and means connecting the plunger that is capable of exerting a progressive increase of power or force on the plunger as it is propelled inward in the 20 cylinder, thus compensating for and overcoming the increasing resistance encountered when compressing air by pressure; third, to have a pump-cylinder of such form and construction that it may be made sufficiently 25 strong for high-pressure service, wholly or in part out of fragile or brittle material—such as glass, porcelain, or cast-iron—which it is very desirable to do for many purposes on account of the cheapness and non-corrosive character 30 thereof, and, fourth, to have a plunger in which the form and arrangement of the parts adapt them to coöperate, so as to make the annular rim of the flexible packing effective as a valve for the inlet of air.

35 In the portion that appertains to the actuating mechanism the gist of my invention consists in the location of the fixed fulcrum for the pivoted end of the lever, because that, being properly located and fixed in position 40 in proper relation to the cylinder, it becomes possible to easily accomplish the second division of the object before stated by diverse means of connecting the lever to the plunger. To render this obvious, several different 45 means for the purpose are illustrated and described, the subjoined claims covering as a means an oscillating and reciprocating link. The other means shown are not particularized in the claims, but are intended to be within 50 their scope.

My invention further consists in the form, construction, and relative arrangement of the

several parts and in combinations whereby the objects heretofore stated are accomplished, all as hereinafter fully set forth, and 55 particularized in the subjoined claims.

In the accompanying drawings, forming part of this specification, Figure 1 is a central section on a plane parallel to the movement of the lever, showing the operating parts 60 covered by subjoined claims in full lines. Fig. 2 is a central cross-section of the plunger enlarged to more clearly show the details. Fig. 3 is a central section on the same plane as Fig. 1, showing operating parts in full lines. 65 Fig. 4 is a top view in full lines.

Like letters indicate like parts in all the figures.

The wall of the cylinder A inclosing the chamber A² is formed tapering in section both 70 inwardly and outwardly, so that its strength is gradually increased from the upper to the lower sections, as shown, this being done to compensate for and resist the increasing expanding force of the air caused when the 75 plunger is depressed. It is also reinforced near to, but above, the bottom A² of the chamber by an encircling flange a, which is also formed to serve as a base-plate and means for securing the pump to a stand or other support. A boss a² is mounted on this flange a and suitably joined to the cylinder. Through this boss is an outlet-passage a³, the outer end 80 of which is closed by a removable plug a⁴. This outlet-passage serves as a means through 85 which to blow out from the chamber A² the surplus oil or other undesirable accumulations. Communicating with the passage a³ is another outlet-passage a⁵, formed and adapted to receive an outlet-valve a⁶ and other 90 connections.

To the upper end of the cylinder A a standard B is rigidly secured in any suitable manner, either with a top plate, as shown, or by direct attachment to the cylinder, as may be 95 preferred. This standard B is so formed and adapted that it will firmly support in a fixed position the fulcrum-bearing B² at a point above the cylinder on a plane parallel to and within a distance from its axis not exceeding 100 one-fourth the cylinder's length and distant from the bottom of the cylinder-chamber A² not more than the distance found by measuring from the bottom of the plunger to the

center of the pivot articulating the link B^4 to the lever B^3 and thence to the center of the fulcrum B^2 and not less than the same measurement would be less the thickness of the 5 plunger. The actuating-lever B^3 is articulated to the fulcrum B^2 in such manner as to allow it an oscillating movement of one hundred and eighty degrees. A link B^4 , forming part of the means connecting the plunger to 10 the fulcrum B^2 , is articulated to this lever B^3 at a point distant from the center of said fulcrum B^2 of not less than half the length of the movement imparted to the plunger nor more than half the length of the cylinder A. 15 The free end of this lever B^3 may extend to a suitable length and there be provided with a hand-grip B^5 . The link B^4 may be duplex or single and of any suitable length, and its other end is articulated directly to a projecting 20 part of the plunger C or to a rod c' , extending from the plunger. This rod or stem c' is firmly attached to the plunger and extends upward a suitable distance to pass through one or more guide-bearings, as B^6 , 25 located above the cylinder and adapted to guide the rod so that the plunger will be carried concentrically within the cylinder and prevented from tilting. The top plate c of the plunger is in form a flat disk having the 30 connecting means c^2 extending from its upper face and a screw-threaded stud c^3 extending from its under face. An upward-extending annular flange c^4 may be provided on its periphery and will serve as an additional means 35 to guide and steady the plunger and prevent it from tilting with the oscillation of the link B^4 . The under face of this top plate has an annular beveled portion c^5 , which extends inward about one-twelfth of its diameter. This 40 beveled portion is pierced with a suitable number of holes c^6 to admit air to the cavity c^7 , formed between this beveled portion and the packing or flexible cup c^8 , which is held in position by the sleeve-nut c^9 , clamping its 45 central part to the under face of the top plate c . The periphery of the flexible cup is a downwardly-extending annular flange c^{10} , wedge-shaped in section, as shown, and the bottom plate c^{11} , having a conical corresponding 50 periphery, is fitted loosely within the flange c^{10} and is likewise provided with a suitably-formed hole through its center adapting it for a short sliding movement on the sleeve-nut c^9 , the head portion of the nut c^9 55 preventing it from coming off. An annular rim c^{12} is raised on the upper side at the peripheral angle, which is suitably larger in diameter than the inner diameter of the beveled portion c^5 of the top plate c . 60 The operation of the plunger parts is as follows: When the top plate c is propelled in the cylinder inward, pressing before it the flexible cup, the annular beveled portion c^5 permits the flexible cup to yield and bend 65 backward, and the resistance of the air in the inclosed cylinder-chamber forces the bottom plate backward, causing its rim c^{12} to

press and bend the flexible cup backward, at the same time the conical periphery of the plate c^{11} acting in conjunction with the wedge-shaped flexible flange c^{10} of the cup forces said flange outward against the wall of the cylinder, thus securing a tight packing of the plunger for each downward movement. As soon as the reverse movement commences a reverse 75 action takes place, the top plate releasing its pressure on the cup and receding from the bottom plate, carrying the central part of the cup with it, the friction of the flange c^{10} retaining it for an instant until the bend of the 80 cup is straightened and space is allowed between the flange and the cylinder-wall for free passage of the incoming air. The inlet air-holes c^6 through the top plate also serve to admit oil for lubricating the plunger and 85 packing.

The cup-leather of the plunger is a valve, as will be seen from the description, and will expand and adapt itself to the varying diameter of the cylinder, and this makes the inside-tapering of the cylinder a very valuable feature, because as the plunger expands itself at the beginning of the downward stroke, due to the compression of the air, it is caused to pack tighter by reason of the tapering of the cylinder as the compression increases, while on the return stroke the plunger cup-leather resumes its contracted condition, thus allowing a space all around it for air to freely pass below the plunger as the latter rises. 100

In operating the pump full stroke the joint articulating the lever to the link moves upward to a point about in line with the axis of the cylinder and downward till the said joint very nearly reaches a point on a right line x drawn from the center of the fulcrum to the center of the bottom of the cylinder-chamber, when the plunger should contact with the cylinder-bottom, thus effectively expelling all the air. It will be seen that in 105 this movement the lever and link acting as a toggle-joint increase the force exerted on the plunger as it encounters increased resistance from the compression of the air.

Having thus described my invention, what 115 I claim as new, and desire to secure by Letters Patent, is—

1. A pump comprising a cylinder and a plunger adapted to reciprocate therein, a standard secured to the cylinder and supporting a fulcrum-bearing, an oscillating lever articulated to said fulcrum-bearing and a link connected to the plunger and articulated to said lever, the said point of articulation passing the axis-line of the cylinder on the downward movement of the lever, the said fulcrum-bearing being supported at a point above the cylinder on a plane parallel to and within a distance from its axis not exceeding one-fourth the cylinder's length, and distant from the bottom of the cylinder not greater than the measurement from the bottom of the plunger to the center of the pivot joining said link to the operating-lever and thence to the 120 125 130

center of the fulcrum, and not less than the same measurement minus the thickness of the plunger.

2. In a pump, the combination with a cylinder and a plunger adapted to reciprocate therein, of a standard secured to said cylinder and supporting fulcrum-bearing, as B^2 , a link, as B^4 , forming one part and a lever, as B^3 , forming another part of the means connecting the plunger to the fulcrum B^2 , the said fulcrum B^2 located at a point above the cylinder on a plane parallel to and within a distance from its axis not exceeding one-fourth of the cylinder's length, and distant 15 from the bottom of the cylinder not greater than the measurement from the bottom of the plunger to the center of the pivot for connecting rod or link B^4 to the operating-lever and thence to the center of the fulcrum, and 20 not less than the same measurement minus the thickness of the plunger, substantially as set forth.

3. In a pump, in combination, a cylinder and a plunger adapted to reciprocate therein, 25 a standard B firmly supporting in a fixed position a fulcrum B^2 , an oscillating lever B^3 articulated to fulcrum B^2 and a link B^4 directly connected to the plunger within the cylinder and articulated to lever B^3 , the said 30 point of articulation passing the axis-line of the cylinder on the downward movement of the lever, the said fulcrum being supported at a point above the cylinder on a plane parallel to and within a distance from its axis not 35 exceeding one-fourth the cylinder's length, and distant from the bottom of the cylinder not greater than the measurement from the bottom of the plunger to the center of the pivot joining link B^4 to the operating-lever 40 and thence to the center of the fulcrum, and not less than the same measurement minus the thickness of the plunger, substantially as set forth.

4. In a pump, as an article of manufacture, a plunger consisting of the following members, in combination a top plate as c having the projections c^2 and c^3 , the guiding flange c^4 and the air-inlet holes c^6 ; a flexible cup-packing as c^8 secured to the top plate by 45 suitable means as c^9 and having a peripheral wedge-shaped flange as c^{10} and a bottom plate having a conical periphery loosely fitted within said flange and adapted to have a short

sliding movement therein as described; these parts coöperating together to make the flange c^{10} act as an inlet-valve, in the manner set forth.

5. A cylinder for air-pumps tapered from its top to the lower portion, both inwardly and outwardly, making the cylinder smaller 55 at the lower portion than at the upper portion on the inside and thicker below than at the top, as set forth.

6. A cylinder for air-pumps tapered from its top to the lower portion both inwardly 60 and outwardly making the cylinder smaller at the lower portion than at the upper portion on the inside and thicker below than at the top, and having an integral reinforcing-flange a above its bottom and a bottom or 70 lower pocket below and beneath the horizontal line of said flange, as set forth.

7. A cylinder for air-pumps tapered from its top to the lower portion interiorly, thus making the cylinder smaller at the lower portion than at the upper portion on the inside, as set forth.

8. In a pump, in combination, a cylinder and a plunger adapted to reciprocate therein and provided with a stem to serve as a steady- 80 ing-rod, a standard B firmly supporting in a fixed position a fulcrum B^2 , an oscillating lever B^3 articulated to the fulcrum B^2 and a link B^4 connected to the plunger within the cylinder and articulated to lever B^3 , the said 85 point of articulation passing the axis-line of the cylinder on the downward movement of the lever, the said fulcrum being supported at a point above the cylinder on a plane parallel to and within a distance from its axis not 90 exceeding one-fourth the cylinder's length, and distant from the bottom of the cylinder not greater than the measurement from the bottom of the plunger to the center of the pivot joining link B^4 to the operating-lever 95 and thence to the center of the fulcrum, and not less than the same measurement minus the thickness of the plunger, substantially as set forth.

Signed at New York, in the county and 100 State of New York, this 11th day of January, 1896.

JOHN N. MCLEAN.
